UNITED STATES PATENT OFFICE.

JOSEPH ARTHUR BLACK, OF CHARLESTON, SOUTH CAROLINA.

TRAFFIC-SIGNAL.

1,250,083.

Specification of Letters Patent. Patented Dec. 11, 1917.

Application filed August 3, 1917. Serial No. 184,221.

To all whom it may concern:

Be it known that I, JOSEPH ARTHUR BLACK, a citizen of the United States, residing at Charleston, in the county of Charleston, State of South Carolina, have invented certain new and useful Improvements in Traffic-Signals, of which the following is a description, reference being had to the accompanying drawings, forming a part hereof.

10 My invention relates to traffic signals such as are used at street crossings to indicate to automobiles and other vehicles whether or not they can be allowed to cross the intersecting street. Such traffic signals usually 15 comprise a vertical rod supported in a base in which it may rotate, carrying at its top cross arms on which are placed the words "Stop" and "Go", and provided with a handle by which the crossing policeman may 20 rotate the rod first in one direction and then in the other to display the "stop" signal or the "go" signal as he may choose.

My invention has for its object to provide 25 an improved device for the purpose indicated in which the vertical rod carrying the signal arms may be operated by foot power or from a distance by a cord or by hand. A further object of the invention is to provide a device for the purpose indicated which 30 may readily be taken down for convenience in transportation and quickly and easily assembled for use. A further object of the invention is to provide a construction which will be simple and inexpensive to construct 35 and which will not readily get out of order and in which the signal can be rotated in one direction only and can be rotated only sufficiently to change the signals by a simple operation.

40 With these and other objects hereinafter set forth my invention consists in the construction, and combination of elements hereinafter described and claimed.

Referring to the drawings:

45 Figure 1 is a perspective view of a traffic signal embodying my invention.

Fig. 2 is a top plan view of the signal arms.

50 Fig. 3 is a top plan view of the supporting standard.

Fig. 4 is a detail view of the upper end of the vertical rod with the lantern and signal arms removed.

55 Fig. 5 is a top plan view of the upper end of the vertical rod.

Fig. 6 is a side view of the two signal arm members separated and

Fig. 7 is a top view of the two signal arm members folded together.

In the drawings 1 indicates a base adapted 60 to rest on the pavement preferably made of heavy plank or otherwise weighted though if preferred it may be of relatively light material and pinned or otherwise secured in place, the essential feature of it being that it 65 shall be adapted to remain where it is placed and form a firm base for the operating parts of the device. This base carries at its center a vertical tube 2 adapted to receive in its open upper end a vertical cylindrical rod 3 70 which is adapted to rotate within the tube 2. This vertical rod 3 carries at its upper end a pair of crossed signal arms 4 and 5 and above these arms is adapted to support a lantern 6 provided with red lenses on two 75 sides.

The upper end of the tube 2 is provided with a series of projections 8 each having one edge 9 vertical and the other edge 10 inclined from the top of the vertical edge 9 80 of one projection to the base of the vertical edge 9 of the next projection. These projections 8 are four in number. The vertical rod 3 is provided with a series of pins 11 85 preferably four in number adapted to fit between the projections 8. The portion of the vertical rod below the pins 11 is of less length than the tube so that the pins will fall to the bases of the projections.

Supported on a slide 17 on the tube 2 below the projections is pivoted a lever 13 the forward or free end of which is provided with an upwardly extending projection 14 having its upper edge inclined as shown at 15 to form a cam surface. To this free 95 end of the lever is attached the upper end of a spring 16 and this free end of the lever is curved to approximate the curvature of the surface of the tube.

When the slide 17 is raised and the outer 100 or rear end of lever 13 is depressed the upper end of slide 17 will raise the pins nearly to the level of the tops of the projections 8 and the cam surface 15 will act on one of the pins 11 to lift the vertical rod 105 until the pins 11 are just above the level of the tops of the projections 8 and the cam will serve as an incline to cause the pins lifted by the cam to start to move toward the pivot 12. This movement will carry the 110

pins over the tops of the projections 8 and they will slide down the inclined faces 10 as the slide 17 is returned to normal position and in so doing will cause the vertical rod 5 to rotate, rotating with it, of course, the signal arms and lantern.

The slide 17 incloses and moves vertically upon tube 2 and carries a projection 18. Secured to this projection 18 is a guide 19 for lever 13. Pivoted to the projection at 20 is a downwardly extending arm 21 which at its lower end is pivoted to the forward end of a foot lever 22 which is loosely pivoted in a pin 23 carried by a support 24. Toward its rear end a link 25 is pivoted to lever 22 the upper end of which is pivotally connected to a link 26 the upper end of which is pivoted to lever 13.

When the outer end of the foot lever 22 is depressed it will be rocked on the support 24 and its forward end through the arm 21 will cause the slide 17 to lift and as the depression is continued it will cause the rear end of the lever 13 to be depressed causing its forward end to lift to throw the pins 11 over the tops of the projections 8.

By attaching a cord 27 to the rear end of the foot lever and leading it through a pulley 28 on the base 1 the foot lever may be operated from any distant point such as a watchman's tower to which the cord may be led.

The upper end of the vertical rod 3 is provided with saw cuts 30 and 31 at right angles to each other, these saw cuts being adapted to receive the signal arms 4 and 5. These signal arms are provided midway of their length with recesses 32 and 33 respectively the recess 32 of arm 4 extending upward half the width of the arm and the recess 33 of the arm 5 extending downward half the width of the arm so that when the two arms are fitted together they can be inserted in the saw cuts 30 and 31 and will be held rigidly at right angles to each other. When removed from the vertical rod the two arms, which are preferably made of sheet metal may be folded together, as indicated in Fig. 7 for convenience in transporting.

The upper end of the vertical rod is adapted to receive a tubular socket 35 carrying the lantern 6. This tubular socket is provided with a notch 36 in its lower edge to fit a pin 37 which may be inserted in a suitable hole in the vertical rod. The tubular socket serves to hold the parts of the upper end of the vertical rod together and may be readily lifted off to permit the signal arms to be removed.

It will, of course, be understood that I do not desire to be limited to the particular construction and arrangement shown and described as it is evident that such construction and arrangement may be modified with-

out departing from the spirit of the invention.

Having thus described my invention what I claim is:

1. A traffic signal comprising a vertical rod carrying signal arms, a base having a cylindrical tube arranged thereon to receive the lower end of the vertical rod having a series of projections at its upper end, a pin carried by the vertical rod adapted to engage said projections and means carried by the base for lifting the vertical rod to disengage the pin. 76

2. A traffic signal comprising a vertical rod carrying signal arms, a base having a cylindrical tube arranged thereon to receive the lower end of the vertical rod having a series of projections at its upper end, a pin carried by the vertical rod adapted to engage said projections, means carried by the base for lifting the vertical rod to disengage the pin, and means for rotating the vertical rod. 80 85

3. A traffic signal comprising a vertical rod carrying signal arms, a base having a cylindrical tube arranged thereon to receive the lower end of the vertical rod having a series of projections at its upper end, a pin carried by the vertical rod adapted to engage said projections, means carried by the base for lifting the vertical rod to disengage the pin, and means acting on the pin for rotating it over the top of a projection on the cylindrical tube. 90

4. A traffic signal comprising a vertical rod carrying signal arms, a base having a cylindrical tube arranged thereon to receive the lower end of the vertical rod having a series of projections at its upper end, a pin carried by the vertical rod adapted to engage said projections, a slide carried by the cylindrical tube for lifting the vertical rod to disengage the pin, and means for lifting the slide. 100 105

5. A traffic signal comprising a vertical rod carrying signal arms, a base having a cylindrical tube arranged thereon to receive the lower end of the vertical rod having a series of projections at its upper end, a pin carried by the vertical rod adapted to engage said projections, a slide carried by the cylindrical tube for lifting the vertical rod to disengage the pin and means carried by the slide for engaging the pin to rotate the vertical rod. 110 115

6. A traffic signal comprising a vertical rod carrying signal arms, a base having a cylindrical tube arranged thereon to receive the lower end of the vertical rod having a series of projections at its upper end, a pin carried by the vertical rod adapted to engage said projections, a slide carried by the cylindrical tube for lifting the vertical rod to disengage the pin and means acting on the pin for rotating it over the top of a pro- 120 125 130

jection on the cylindrical tube comprising a lever pivoted on the slide.

7. A traffic signal comprising a vertical rod carrying signal arms, a base having a cylindrical tube arranged thereon to receive the lower end of the vertical rod having a series of projections at its upper end, a pin carried by the vertical rod adapted to engage said projections, a slide carried by the cylindrical tube for lifting the vertical rod to disengage the pin and means acting on the

pin for rotating it over the top of a projection on the cylindrical tube comprising a lever pivoted on the slide and means for lifting the slide and operating said lever.

15

8. In a traffic signal a pair of signal arms formed of strips of sheet metal interlocked midway of their length so as to be capable of folding together.

In testimony whereof I affix my signature 20
this 31st day of July 1917.

JOSEPH ARTHUR BLACK.
